UNITED STATES PATENT OFFICE.

HOWARD L. PARK, OF READING, MASSACHUSETTS.

FORM FOR MAKING CEMENT OR CONCRETE STEPS.

1,124,327.

Specification of Letters Patent.

Patented Jan. 12, 1915.

Application filed January 2, 1912. Serial No. 668,973.

To all whom it may concern:

Be it known that I, HOWARD L. PARK, a citizen of the United States, residing at Reading, in the county of Middlesex and State of Massachusetts, have invented certain new and useful Improvements in Forms for Making Cement or Concrete Steps, of which the following is a specification.

This invention has for its object to provide a simple and efficient form for making cement or concrete steps, and also to provide improved means for adjusting the parts constituting the form so as to adapt the same to the height of the risers and width of the treads which the steps are to have.

The invention also has for its object to provide a novel construction and arrangement of parts which can be easily and quickly assembled and adjusted to conform to the desired dimensions of the steps.

In order that the invention may be better understood, reference is had to the accompanying drawing in which—

Figure 1 is a perspective view of the form set up ready for use. Fig. 2 is a vertical section on the line 2—2 of Fig. 1. Fig. 3 is a perspective view of one end of one of the end members of the mold. Fig. 4 is a sectional detail showing a slight modification.

Referring specifically to the drawing, the form consists of a series of adjustably connected end members which are spaced apart laterally according to the desired width of the steps. These members support trans-

verse vertically arranged boards 5 which determine the risers of the steps. The end members are each in two sections, indicated at 6 and 7, respectively, said sections being boards of suitable length which are placed vertically and face-to-face, with the section 7 extending above the top edge of the section 6. The two sections are held together near one of their ends by a bolt 8 which is secured by a nut 9, the section 7 having a vertical slot 10 through which the bolt passes. A bolt 11 fastens the sections together near their other ends, said bolt being also secured by a nut 12 and passing through a slot 13 in the section 7. On the bolt 11 is

pivoted a link 14 which depends from said bolt and supports at its lower end one end of a longitudinally slotted bar 15, the slot of said bar being indicated at 16. The other end of the bar is supported by the lower end of a link 17 which is pivoted to and depends from a bolt 18 carried by the section 6.

The bar 15 is located below the bottom edge of the section 6, and through the slot 16 thereof passes a bolt 19 carrying at one of its ends a cam-clamp 20 for tightening up the same. If desired, a hand-nut 21, as shown in Fig. 4, may be provided for the same purpose.

The function of the bar 15 and the bolt 19 is to connect one of the herein-described sectional end members to a similar member below the same, the several end members being all alike, and connected in a like manner. The section 6 of the end member which is below the one first described has a vertical slot 22 through which the bolt 19 passes. In assembling the several end members, the sections thereof are adjusted so that the top edge of the section 7 is flush with the bottom edge of the section 6 of the next member above. The end members are also arranged so that each succeeding member projects beyond one end of the next member below for a distance equal to the width of the tread of the steps. This width is readily varied as the slots 16 permit longitudinal adjustment of the members with respect to each other. The desired height of the risers is attained by the vertical adjustment of the sections 6 and 7 relative to each other, the slots 10, 13 and 22 permitting such adjustment.

Across the ends of the end members, which are below the projecting portion of the end member above, is placed the board 5 which forms the face of the risers, said board being held in place by brads 24 carried by the sections 6 and 7, and projecting from one end thereof. The height of the board is such that its top and bottom edges are flush with the corresponding edges of the end member. Riser boards of different heights will be employed according to the desired height of the risers.

To the ends of the sections 6, opposite the ends against which the riser boards 5 are placed, are secured metal strips 25 which overlap the corresponding ends of the sections 7.

In operation, a pair of end members are set up, suitably spaced apart according to the width the steps are to have, and braced by pins or any suitable means 26 so that they may remain in upright position. A riser board 5 is now placed in position for the first riser, and cement or concrete is filled in behind the same for the first step. Another pair of

end members and a riser board is next put in place and the material is filled in behind the latter to make the second step. This operation is continued until the desired number of steps are formed. The treads are formed by leveling off the material flush with the upper edges of the riser boards. The material may be held in place on the sides of the mold by boards. The steps are usually built against a buttress, but if necessary boards can be used on the sides.

In the ordinary method of molding cement or concrete steps, a form is built which is practically a complete set of stairs or steps of the desired width, length and height, and this form is inverted and filled, after which the form is knocked away. This method is expensive as it requires a skilled carpenter to build the form, and the form also cannot be used again. The form which is the subject of the present invention can be used over and over again, and can be easily and quickly set up and adjusted to the desired dimensions of the steps, and does not require skilled labor. It will therefore be evident that a cement step can be cheaply made. The links 14 work on their pivots very slightly so that if there should be any play, the forward pressure of the material would tend to tighten the connections. The pressure sidewise is very small, and the end members are held against spreading by the riser boards 5.

I claim:

1. A form for molding steps comprising series of laterally spaced end members mounted one above the other, said members being adjustable relative to one another to project at their rear ends beyond the corresponding end of the member below according to the width of the step-tread, and each

of said members consisting of sections which are connected in face to face relation and adjustable vertically relative to each other, and riser forming members mounted on the aforesaid rear ends of the end members.

2. A form for molding steps, comprising laterally spaced and vertically slotted end members mounted one above the other and projecting at one of their ends beyond the corresponding end of the member below, a pair of links pivoted to each of said members and depending therefrom, a longitudinally slotted bar carried by each pair of the links, a clamping member passing through the slot of the bar and the vertical slot of the end member which is below the end member carrying the links, and riser-forming members mounted on the aforesaid ends of the end members.

3. A form for molding steps, comprising laterally spaced and vertically slotted end members mounted one above the other and projecting at one of their ends beyond the corresponding end of the member below, and each of said members consisting of adjustable sections to vary the height thereof, a pair of links pivoted to each of said members and depending therefrom, a longitudinally slotted bar carried by each pair of the links, a clamping member passing through the slot of the bar and the vertical slot of the end member which is below the end member carrying the links, and riser-forming members mounted on the aforesaid ends of the end members.

In testimony whereof I affix my signature in presence of two witnesses.

HOWARD L. PARK.
